UNITED STATES PATENT OFFICE.

ANDERS HOLMER, OF CHICAGO, ILLINOIS.

SUIT-HANGER.

No. 854,420.

Specification of Letters Patent.

Patented May 21, 1907.

Application filed August 6, 1906. Serial No. 329,330.

To all whom it may concern:

Be it known that I, ANDERS HOLMER, a subject of the King of Sweden, residing at Chicago, in the county of Cook and State of Illinois, have invented certain new and useful Improvements in Suit-Hangers, of which the following is a specification.

The object of this invention is the production of an improved combined coat and trousers hanger.

In the accompanying drawings, Figure 1 is a perspective view of a combined coat and trousers hanger embodying the features of my invention. Fig. 2 is a side elevation thereof. Fig. 3 is a sectional view taken on the plane of dotted line 3 3 of Fig. 2. Fig. 4 is a section on dotted line 4 4 of Fig. 3.

The embodiment herein shown of my invention comprises a cross-bar 1 properly shaped to support a coat, the ends of said cross-bar being adapted to be inserted beneath the shoulders of the coat in the usual manner. Located beneath said cross-bar and secured thereto is a trousers hanger, said hanger being formed of an integral piece of wire of suitable gage, the ends of said wire forming attaching posts 2 extending into and secured within openings (not shown) in the lower side of the cross-bar 1. The middle portion of the wire is bent to form two arms 3, each of said arms being doubled over upon itself so that the forward and rear portions 3^a and 3^b thereof lie substantially parallel and relatively close to each other.

As shown in the drawings, each of the arm-portions 3^a and 3^b is double, providing a wider bearing upon the trousers-legs than would be obtained by the use of an arm formed of a single strand of wire. The two strands of wire in each of said arm-portions lie in substantially the same vertical plane, as shown

in Figs. 3 and 4, the lower strand or member of the rear arm-portion 3^b being bent or offset to pass behind the upper member of said arm-portion as seen in Fig. 3. A hook 4 fixed to the cross-bar 1 provides means for suspending the suit-hanger from any convenient or suitable support.

In use the cross-bar 1 receives the coat, and the lower portions of the trousers-legs are secured in the trousers-hanger by inserting the creased sides between the arm-portions 3^a and 3^b of each of the arms 3, as represented in Fig. 2. The double thickness of the lower ends of the trousers-legs provides sufficient thickness of material above the arms 3 to prevent the trousers from slipping out of the trousers-hanger.

The portion of the suit-hanger herein designated as the trousers-hanger may be used to support a skirt, the waist portion of the skirt being inserted into the double arms 3 in the manner hereinbefore described for trousers.

I claim as my invention:

In a suit-hanger, in combination, a cross-bar and a trousers-hanger secured to said cross-bar, said trousers-hanger being formed of an integral piece of wire, the ends of which form attaching posts secured to the under side of said cross-bar, the middle portions of the wire being bent to provide two arms each comprising two arm-portions lying relatively near each other, each of said arm-portions consisting of two members, the outer ends of said double arms being closed and the two members of each of said arm-portions lying in substantially the same vertical plane.

ANDERS HOLMER.
